(57) **CLAIM**

The ornamental design for a basketball basket, as shown and described.

DESCRIPTION

FIG. 1 is a front-right-top perspective view of a basketball basket, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a perspective view showing a second embodiment of the claimed design, wherein two springs respectively are formed on the left and the right of the claimed design;

FIG. 9 is a front elevational view of FIG. 8;

FIG. 10 is a rear elevational view of FIG. 8;

FIG. 11 is a left elevational view of FIG. 8;

FIG. 12 is a right elevational view of FIG. 8;

FIG. 13 is a top plan view of FIG. 8; and,

FIG. 14 is a bottom plan view of FIG. 8.

The broken line showing of the net is for illustrative purposes only and forms no part of the claimed design.
